UNITED STATES PATENT OFFICE.

WILLIAM H. HART, JR., OF PHILADELPHIA, PENNSYLVANIA.

MAILING-ENVELOP.

1,179,718.

Specification of Letters Patent. Patented Apr. 18, 1916.

Application filed April 14, 1915. Serial No. 21,352.

To all whom it may concern:

Be it known that I, WILLIAM H. HART, Jr., a citizen of the United States, residing in the city and county of Philadelphia, State of Pennsylvania, have invented a new and useful Mailing-Envelop, of which the following is a specification.

My invention consists of a mailing envelop or package which is composed of a body and a closing flap thereon, and a wedging key which is adapted to engage said flap and body to hold the former tightly on the latter, but permit of the opening of said flap without fracturing or injuring the envelop.

It consists also of means on said key for preventing accidental displacement thereof from the envelop.

The invention is satisfactorily illustrated in the accompanying drawing, but the important instrumentalities thereof may be varied, as long as they are included in the scope of the claim.

Figure 1 represents a rear elevation of an envelop embodying my invention, the same being in closed condition. Fig. 2 represents a similar elevation of a portion of the envelop in open condition. Fig. 3 represents a transverse section on line $x-x$ Fig. 1. Fig. 4 represents an elevation of the key employed. Fig. 5 represents a rear elevation of another embodiment of the invention. Fig. 6 represents a rear elevation of a portion of the envelop shown in Fig. 5 in open condition. Fig. 7 represents a transverse section on line $y-y$ Fig. 5. Fig. 8 represents an elevation of a detached member of Fig. 5.

Similar numerals of reference indicate corresponding parts in the figures.

Referring to the drawings, 1 designates an envelop composed of the body 2 and the closing flap 3 thereon. In the back 4 of said body are the openings 5 which leaves between them the bar 6 which extends in the longitudinal direction of the envelop. In the flap 2 is an opening 7 which is so disposed that when said flap is closed, said opening registers with said bar and its wall extends over the latter, the diameter of said opening being greater than the width of said bar.

8 designates a key which is formed of cardboard or other suitably light and strong material, it being wedging in shape and adapted when the flap is in closed condition to be passed through one side of the open-

ing 7, then under the bar 6, and then through the other side of said opening, its opposite ends then resting on the portions of the flap about the wall of said opening, whereby the bar 6 and consequently the body of the envelop is interlocked with the flap thereof, thus retaining the flap in closed condition. The key owing to its wedge shape tightens against the upper and lower edges of the bar 6 and serves to hold the latter tightly and snugly in the opening 7.

In order to prevent accidental displacement of the key there is formed thereon the tooth 9 which is cut or punched out of the material of said key and so disposed thereon that when the key is pushed into position to comparatively full extent, the tooth is pressed outwardly whereby on slightly withdrawing the key the tooth overlaps the adjacent side of the bar 6 as a projecting shoulder, and so prevents outward motion of the key and causing the latter to retain its position in or under the bar 6.

It will be seen that if a postal official wishes to examine the contents of the envelop, the tooth 9 and key 8 are properly manipulated so as to remove the latter, when the flap is free to be raised, and the body of the envelop to be opened, the contents thus being made visible, after which the flap may be closed and the key restored to its locking position, it being noticed that the envelop has been retained intact without fracture or injury thereto.

In Figs. 5 and 6 I show a key with a tooth 9 similar to that shown in Figs. 1 and 3, the same being employed to connect the supplemental flap 12 with the flap 3. In this case, said flap 12 has the bar 6 therein, the same being back of the opening 7 in the flap 3 so that the key may operate to lock said supplemental flap to the flap proper of the envelop, but said supplemental flap has adhesive material 13 on the back thereof, whereby it may be attached to the back of the body of the envelop as a fixture thereof, so that when the key is removed while the supplemental flap remains connected with the body of the envelop, the latter is disconnected from said supplemental flap and so may be opened for inspection of the contents of the envelop without in any manner fracturing or injuring the envelop.

While I denominate the device as a mailing envelop it may be used for general business purposes, as a package or folder to con-

tain merchandise or goods, and carry or transmit the same in closed condition to its place of destination.

Having thus described my invention what 5 I claim as new and desire to secure by Letters Patent, is:—

In an envelop of the character stated composed of a body and closing flap, the latter having an opening therein, and the former 10 having therein a plurality of openings forming a vertically-extending bar which is adapted to occupy a position behind said

opening in the flap, and a key which is adapted to be inserted rearward of said bar and over the adjacent portions of said flap 15 aside of the opening therein, said key having thereon a bendable tongue integral with the same adapted to overlap the exterior of said bar on a side thereof.

WILLIAM H. HART, JR.
